2,001,906

TREATMENT OF HYDROCARBON OILS

Vladimir Ipatieff, Chicago, Ill., assignee to Universal Oil Products Company, Chicago, Ill., a corporation of Delaware

No Drawing. Application October 26, 1932,
Serial No. 629,615

3 Claims. (Cl. 196—18)

This invention relates to the treatment of hydrocarbon oil, and refers more particularly to the treatment of the low boiling naphthas and gasolines produced from crude petroleums by fractionation under conditions involving substantially no cracking.

In a more specific sense the invention has reference to a process for treating said "straight run" gasolines to improve their quality with respect to gum and color-forming compounds present and in a specific sense in regard to improving their anti-knock value and increasing their yield. The details of the process whereby these desirable refining effects are accomplished are given in the following specification.

In a general way the gasoline fractions present in crude petroleums referred to as straight run gasolines, which may be removed therefrom by fractionation at moderate temperatures and pressures, reflect the character of the crude petroleum, that is, the proportions of such hydrocarbon groups as paraffins, olefins, naphthenes, aromatics and the sulfur and nitrogen compounds are usually present in approximately the same ratio as they are present in the crude petroleum as a whole. Although there are cases of considerable divergence from this rule, it has been repeatedly noted that the gasolines from paraffinic crudes such as those from the Pennsylvania and some of the Mid-Continent fields are highly paraffinic and highly knocking in character. The gasolines from the Mid-Continent field crudes and some of the Gulf crudes have an intermediate character in respect to anti-knock value, indicating possibly the presence of relatively higher percentages of cyclic compounds of the nature of naphthenes or of isoparaffins. Certain crude oils from the Pacific Coast producing areas and some Texas fields yield gasolines of comparatively high anti-knock value, owing to the cyclic character of the crude oils.

These observations as to the variable character of straight run gasolines are merely adduced in a general way to show that different gasolines or naphthas may require different degrees of treatment according to the process of the invention to be presently disclosed in order to render them up to the prevailing market standards for anti-knock value.

The present invention comprises a process of treatment whereby the character of the hydrocarbons present in straight run gasolines is altered in the direction of increased anti-knock value so that the need for excessive cracking of heavy hydrocarbon fractions to produce high

anti-knock blending gasolines and the losses attendant upon such a type of operation are in many cases obviated.

The process furthermore effects a conservation of some of the waste products of cracking processes which are caused to combine with certain hydrocarbon groups in straight run gasolines so that the overall yield of product is increased.

In one specific embodiment the invention comprises treatment of straight run gasolines with olefins in the presence of sulfuric acid to produce hydrocarbons which add anti-knock value to the gasoline and at the same time to produce other desirable treating effects.

The term "olefin" as used within the concept of the present invention comprises any compound of carbon and hydrogen of open chain structure and containing one or more double bonds between carbon atoms. The following tabulation gives a few of the lower boiling members of the ethylene series which consists of homologues of the base substance ethylene containing one double bond:

Table No. 1

Ethylene	$\text{CH}_2=\text{CH}_2$	-102.7°	25
Propylene	$\text{CH}_3\text{CH}=\text{CH}_2$	-48° gaseous	
Ethyl ethylene (n-butylylene).	$\text{CH}_3\text{CH}_2\text{CH}=\text{CH}_2$	-5°	
Plane-sym. dimethyl ethylene	$\text{CH}_3\text{CH}=\text{CH}.\text{CH}_3$	(+1°)	
Axial-sym. (1,3- butylene).	$(\text{CH}_3)_2\text{C}=\text{CH}_2$	(+2.5°)	30
Unsym. dimethyl ethylene (iso-butylylene).	$\text{CH}_3\text{CH}_2\text{CH}_2\text{CH}=\text{CH}_2$	-6°	
n-Propyl ethylene (alpha- amylene).	$(\text{CH}_3)_2\text{CH}.\text{CH}=\text{CH}_2$	+39°	
Isopropyl ethylene (al- pha-isomethylene).	$\text{CH}_3\text{CH}_2\text{CH}=\text{CH}.\text{CH}_3$	+21°	
Sym. methyl ethyl ethylene (beta-amylene).	$\text{CH}_3\text{CH}_2\text{CH}=\text{CH}.\text{CH}_3$	+36°	35
Unsym. methyl ethyl ethylene (gamma-amylene).	$\text{CH}_3\text{CH}_2\text{C}=\text{CH}.\text{CH}_3$	+31°	
Trimethyl ethylene (beta-isomethylene).	$(\text{CH}_3)_2\text{C}=\text{CH}.\text{CH}_3$	+36°	
Tetramethyl ethylene...	$(\text{CH}_3)_2\text{C}=\text{C}(\text{CH}_3)_2$	+73°	40

Beginning with compounds of four carbon atoms, the table shows that a number of isomers are possible corresponding to different positions of the double bond and the presence of tertiary or quaternary carbon atoms, the number of possible isomers increasing as the number of carbon atoms increases. From these considerations it is evident that for the ethylene series alone a large number of different olefins may be employed either singly or in admixture for condensation with gasoline hydrocarbons according to the process of the invention.

The invention may further comprise the utilization of open chain unsaturated hydrocarbons

of the acetylene or the diolefin series comprising such compounds as acetylene, butadiene, etcetera, and their homologs. While pure compounds of this character and even ethylene itself do not react readily even with aromatics in the presence of sulfuric acid catalyst, there is apparently some alkylation by these compounds when used in admixture with other olefins as occurs in the case of gases from cracking processes.

The reactions involved in treatments according to the process of the invention are of considerable complexity owing to the large number of hydrocarbon types represented in the gasolines treated on the one hand and the large number of olefins which may be employed on the other hand to alter the character of the gasoline. Merely to exemplify to some extent the character of the reactions which may occur, those which take place when a single olefin such as propylene is caused to join with benzol to produce an alkylated derivative may be considered. When gaseous propylene is passed into a well-stirred mixture of benzol and concentrated sulfuric acid in proper proportions, the propylene is apparently sulfonated at first to produce a mono-propylsulfuric acid, and there are indications that the benzol may be sulfonated to some extent. The sulfuric acid derivatives then react to form a propylated benzol and regenerate to a large extent the sulfuric acid so that the net result of the reactions is expressed by the following equations which show the formation of mono- and di-isopropyl benzol:

The relative proportions of the mono- and di-derivatives will depend upon such factors as the relative proportions of the two hydrocarbons employed, the rate of introduction of the propylene into the acid-aromatic mixture, the strength of the acid and particularly the temperature which in the majority of cases of this character is best maintained at least at atmospheric temperature to minimize loss of olefins by polymerization. In the above reactions propylene represents any of the homologs of ethylene, although ethylene itself is not specially reactive. Similarly, benzol represents any of the aromatic series of hydrocarbons and may also typify the polynuclear aromatics such as naphthalene and anthracene. However, the proportion of these polynuclear aromatics is undoubtedly very small in straight run gasoline fractions which commonly boil under 437° F.

The reactions given above in connection with olefins and aromatics are obvious and readily understandable to persons versed in organic chemistry. However, it is advanced as a particular feature of the present invention that unusual and unexpected results have been obtained when treating gasolines with olefins and olefin mixtures in the presence of sulfuric acid when the gasolines are of a paraffinic character as produced from Pennsylvania crude oils and contain substantially no hydrocarbons of a distinctly aromatic character though possibly a considerable percentage of naphthenes. Owing to the difficulties of exact analysis in the case of hydrocarbon oil mixtures only a limited amount of data is available on the subject of the proximate

composition of gasolines, but considerable qualitative and some semi-quantitative experiments have indicated that the so-called paraffinic gasolines may consist not only of normal or straight chain paraffins, but also to a large extent of so-called iso or branched chain paraffins and cyclic compounds of a saturated or partially saturated character such as the naphthenes and mixed alkyl derivatives thereof. The course of the reactions which lead to the improvements noted in the case of straight run paraffinic gasolines when treated by the process of the present invention may consist in re-arrangements among the substituting groups either in the open chain or closed chain hydrocarbons, or it may comprise the direct addition of olefins to central carbon atoms in the paraffinic chains. Such reactions cannot be closely followed owing to the difficulties in securing reliable analytical data.

The following equations in addition to those previously given suggest further reactions which may take place when olefins are contacted with straight run gasoline in the presence of sulfuric acid under regulated conditions. In the case of a straight chain paraffin such as pentane, the following equation expresses a possible reaction:

Owing to the observed increase in anti-knock value which occurs many times in the alkylation of straight run gasolines according to the process of the invention it is probable that at least some of the methyl or other alkyl groups attach to the carbon chain in a central position so that iso compounds are formed, since it is known that hydrocarbons of higher anti-knock value are obtained when the carbon atoms are arranged more compactly.

The equation given below suggests a reaction which might be presumed to take place between an olefin and a naphthene or a partially hydrogenated aromatic of a mixed or terpene-like character:

Similar reactions may occur with aromatic hydrocarbons which may be present in straight run gasolines. The foregoing suggested reactions merely indicate possible trends and many other and more complicated reactions may occur owing to the possibility of the shifting of labile hydrogen atoms and alkyl groups such as methyl, ethyl, propyl, etcetera.

Also, where olefins are contacted with sulfuric acid some polymerization will occur among the olefins themselves as well as the alkylation reactions described. Also, these reactions may be controlled by proper contacting of the olefinic hydrocarbons with the gasoline hydrocarbons so that there is a decreased tendency toward the formation of compounds of high molecular weight. Owing to the low formation of tarry polymers observed in practically all cases it is probably that if polymerization reactions occur that they do not pass beyond the stage of dimers and trimers which of themselves are valuable compounds and add anti-knock value to the gasoline hydrocarbon mixture.

In some cases the sludge from the process may be recirculated and reused. It is to be pointed out that sulphuric acid sludges resulting from the treatment, or from some similar treatment, may

be employed either alone or in combination with fresh acid. A commercial application of the process of the invention is well exemplified in the treatment of a straight run gasoline with the gases from a cracking process. In such operations several modes of procedure will present themselves to those conversant with commercial practices. In the simplest case sulfuric acid of regulated strength (usually from 85% to 95%) may be stirred into a stationary body of gasoline in a batch agitator and a stream of olefin-containing gases bubbled through the suspension through a spray or other distributing means. It is usually preferable to have cooling coils immersed in the reaction mixture so that excessive temperature rise is avoided.

The use of towers makes possible continuous operation, the acid, olefinic gases and gasoline being separately injected into a mixing box of some character at the top of the column and the mixture allowed to flow by gravity down over pans or perforated plates so that more or less complete reaction is assured by the time the reaction constituents reach the bottom of the tower. In some cases the acid and gasoline may be caused to flow downwardly and the stream of olefinic gases directed upwardly through the tower to effect a counterflow treatment.

An example involving the treatment of a Pennsylvania straight run gasoline with the gases produced in cracking a fuel oil distillate from the same crude may be cited. The gasoline before treatment had the following properties:

35 Gravity ° A. P. I.	64.8	35
Initial boiling point.	104° F.	
10% over at	154	
20% over at	183	
30% over at	203	
40% over at	220	
50% over at	226	
60% over at	252	
70% over at	269	
80% over at	290	
90% over at	324	
End point (97.5%)	376	

When a blend of 90 parts of a test gasoline showing 67.5 octane number and 10 parts of this gasoline were tested, an anti-knock value of 52 octane number was obtained.

This gasoline was treated with an olefinic gas mixture containing approximately 40% propylene by volume, this gas being produced in conjunction with cracking the fuel oil distillate to produce gasoline. Acid of 1.835 specific gravity was used. In the run as conducted 5.5 gallons of the straight run gasoline, 3.5 gallons of acid and 1860 cubic feet of the gas per hour were injected into a mixing box at the top of a tower through which the injected materials passed downwardly. As a result a volume of 235% of alkylated hydrocarbons was produced based on

the volume of the original gasoline. The properties of the alkylated product were as follows:

Gravity ° A. P. I.	55.6	
Initial boiling point °F.	86	
10% over at	177° F.	5
20% over at	210	
30% over at	238	
40% over at	258	
50% over at	298	
60% over at	344	10
70% over at	397	
80% over at	490	
End boiling point (85%)	542	

When this product was again used in 10% blend with the reference fuel of 67.5 octane number, the blend tested 83 octane number which indicates the remarkable improvement effected by the treatment since the average boiling point of the product was considerably higher than the original gasoline and yet the anti-knock value was much higher as shown by comparing the octane numbers.

The blending fluid thus produced could be distilled after a caustic wash with no change in color or odor or the development of sulfur compounds due to decomposition of soluble acid esters.

The foregoing specification has described and disclosed the general and broad character of the invention and the example is sufficiently indicative of its value from a commercial standpoint. However, the invention is not limited in scope to the exact details of the descriptive material or the experimental data given.

I claim as my invention:

1. A process for the production of high anti-knock motor fuel, which comprises simultaneously subjecting a straight run distillate containing gasoline hydrocarbons and gases resulting from a cracking process to the action of sulphuric acid, and reacting olefins contained in the gases with a portion of the distillate to form alkylated derivatives of high anti-knock rating.

2. A process for the production of high anti-knock motor fuel, which comprises simultaneously subjecting a straight run distillate containing gasoline hydrocarbons and gases containing olefin hydrocarbons to the action of sulphuric acid, and reacting olefins contained in the gases with a portion of the distillate to form alkylated derivatives of high anti-knock rating.

3. A process for the production of high anti-knock motor fuel, which comprises simultaneously subjecting a straight run distillate containing gasoline hydrocarbons of a predominately paraffinic character and gases containing olefin hydrocarbons to the action of sulphuric acid, and reacting olefins contained in the gases with a portion of the distillate to form alkylated derivatives of high anti-knock rating.

VLADIMIR IPATIEFF.
